LIGHT FIXTURE

Elsie Crawford, 1930 Waverly, Palo Alto, Calif.

Filed Oct. 23, 1964, Ser. No. 82,303

Term of patent 7 years

(Cl. D48—23)

FIG. 1 is a plan view of the light fixture embodying my new design.

FIG. 2 is a bottom view.

FIG. 3 is an elevation view.

I claim:

The ornamental design for a light fixture, substantially as shown.
